UNITED STATES PATENT OFFICE.

WILLIAM J. DAVIS, OF MONTREAL, QUEBEC, CANADA.

SHARPENING DEVICE FOR SAFETY-RAZOR BLADES.

Application filed June 24, 1921. Serial No. 480,212.

To all whom it may concern:

Be it known that I, WILLIAM J. DAVIS, a subject of the King of Great Britain, residing at Montreal, in the Province of Quebec, 5 Canada, have invented certain new and useful Improvements in Sharpening Devices for Safety-Razor Blades; and I do hereby declare that the following is a full, clear, and exact description of the invention, such as 10 will enable others skilled in the art to which it appertains to make and use the same.

The present invention relates to new and useful improvements in sharpening devices for safety razor blades and more particularly 15 to the blades for "Auto Strop" razors.

The primary object of the invention is the provision of a device such as above referred to including novel means for holding the blade while the latter can be sharpened 20 either on the usual strop or hone.

Another object of the invention is the provision of a holder for blades so arranged that it will engage the blade and firmly hold the same while the latter is being stropped 25 in the usual manner, and which is of such construction that the blade can be quickly removed therefrom.

A still further object of the invention is the provision of a sharpening device for razors and the like, which will be comparatively simple and inexpensive to manufacture, reliable and efficient in use, and readily operated.

With the above and other objects in view, 35 the present invention resides in the novel features of construction, formations, combinations, and arrangements of parts to be hereinafter more fully described, claimed and illustrated in the accompanying drawing, forming a part of the present application and in which:

Figure 1 is a side elevation of the invention showing the razor blade in position;

Figure 2 is an edge view thereof;

Figure 3 is a longitudinal sectional view taken therethrough;

Figure 4 is a detail perspective view of the locking plunger removed; and,

Figure 5 is a similar view of the razor 50 blade removed.

Referring now to the accompanying drawing by corresponding characters of reference throughout the several views, the numeral 6 designates in general my improved razor 55 sharpening device which consists of a tubular handle 7, one end of which is closed by a

cap portion 8, while the opposite end thereof is flattened as at 9 to produce a substantially rectangular portion 10 formed at one end with a lip 11 which has an inwardly directed lug 12 formed thereon adapted to engage the notch 13 formed in one end of the blade 14 to be sharpened.

A spring actuated plunger 15 is slidable in the end of the sleeve adjacent the back portion 10 and is provided at its inner end with a projection 16 designated to fit within one end of a spring 17, the opposite end of which bears against the cap 8, forcing the plunger to its outermost position.

A pin 18 projects from the side of the plunger 15 through a slot 19 formed in the handle 7 adjacent one end thereof and is provided with a terminal head 20 which serves as a finger grip for the operator in actuating the plunger 15. The outer end of the plunger 15 is bevelled as at 21 to fit within the groove 22 provided in the opposite end of the blade 14, while the forward side of the plunger 15 is thinned or cut away as at 23 to prevent interference when the blade is being sharpened by its engagement with the usual strop or hone not shown in the drawing.

The outer surface of the handle 7 may be milled, as shown at 24 to provide a means whereby the same can be gripped by the operator when desired and to prevent slipping while the back portion 10 is relatively flat, which also prevents interference while in operation.

From the foregoing description taken in connection with the accompanying drawing, it will be manifest that a razor sharpening device is provided which is particularly designed for use in holding safety razor blades of the "Auto Strop" type, and which when held therein will permit of the blade being honed or stropped in the usual manner, and it should be further understood in this connection that various minor changes in the specific details of construction can be resorted to within the scope of the appended claim without departing from the spirit or sacrificing any of the advantages of the invention.

Having thus fully described the invention, what I claim as new and desire to protect by Letters Patent is:—

The herein described sharpening device for safety razor blades, comprising a hollow tubular handle, a back formed upon one end of the handle, a lip formed upon the outer

end of said back, a lug provided upon the
lip for engaging a notch provided in one
end of the safety razor blade, a plunger
mounted in said handle, a pin extending
from the plunger through a slot in said han-
dle, a projection upon said plunger, a spring
positioned within the handle and engaging
the projection of the plunger, one side of the
plunger being cut away and one end of the
plunger being bevelled to engage a notch ¹⁰
formed in the opposite end of the razor
blade, substantially as and for the purposes
set forth.

In witness whereof I have hereunto set my
hand.

WILLIAM J. DAVIS.
